WILLIAM S. GUTHRIE, OF TERRELL, TEXAS.

VALVE MECHANISM FOR CARBURETERS.

1,029,606.

Specification of Letters Patent. Patented June 18, 1912.

Application filed June 25, 1910. Serial No. 568,905.

To all whom it may concern:

Be it known that I, WILLIAM S. GUTHRIE, a citizen of the United States, residing at Terrell, in the county of Kaufman and State of Texas, have invented a new and useful Valve Mechanism for Carbureters, of which the following is a specification.

The invention relates to improvements in valve mechanism for carbureters for use on 10 internal combustion engines.

The object of the present invention is to provide a simple, efficient and practical valve mechanism, equipped with a fuel valve controlling a fuel supply and operating 15 with a short stroke of only sufficient movement to supply the desired amount of fuel and without affecting the draft of the engine, whereby the fuel valve is prevented from hammering its seat or interfering with 20 the free passage of the mixture of air and fuel.

A further object of the invention is to provide a valve mechanism, having a fuel valve and provided with a fluid valve controlling the opening of the fuel valve, and having a constant suction controlled travel unaffected by the amount of movement of the fuel valve or any adjustment thereof.

With these and other objects in view, the 30 invention consists in the construction and novel combination of parts hereinafter fully described, illustrated in the accompanying drawings, and pointed out in the claims hereto appended; it being understood that 35 various changes in the form, proportion, size and details of construction, within the scope of the claims, may be resorted to without departing from the spirit or sacrificing any of the advantages of the invention.

In the drawings:—Figure 1 is a vertical sectional view of a carbureter including valve mechanism, constructed in accordance with this invention. Fig. 2 is a horizontal 45 sectional view on the line 2—2 of Fig. 1. Fig. 3 is a similar view on the line 3—3 of Fig. 1.

Like numerals of reference designate corresponding parts in all the figures of the 50 drawings.

In the embodiment of the invention illustrated in Figs. 1 to 3 of the accompanying drawings, the valve casing is composed of upper and lower sections 1 and 2, the upper 55 section being of elbow formation and pro-

vided at the lower end with an inwardly extending annular portion 3, having interior screw threads to receive a projecting threaded portion 4 of the lower section 2 of the casing. The lower section is exteriorly recessed at its upper end to receive the lower end of the upper section of the casing for arranging the parts in flush relation.

The valve casing may be modified in a 65 variety of ways, but in the accompanying drawings I have shown only one form of valve casing. The projecting portion 4 of the lower section has an inner cylindrical face and forms a cylindrical passage-way, 70 which is controlled by a fluid valve 5 of circular form, provided with a vertical tubular stem 6 and arranged to receive vertical stem 7 of a fuel valve 8. The fluid valve 5 is provided at its periphery with a depending exteriorly beveled annular flange 9, forming a tapering periphery and adapted when the valve is raised to provide an opening for the passage of mixture to the engine. The tubular valve stem 80 6 is provided with a depending extension 10, operating in a lower web or spider guide 11, said guide being arranged in the casing below the fluid valve and above the seat or upper end of the fuel 85 passage and said extension engaging a collar 12 of the fuel valve to seat the same against a valve seat 12^a. The fluid valve is held against rotary movement in the 90 guide by a pin 5^a arranged to engage the 95 guide. By employing the lower central tubular guide, which is arranged between the seat for the fuel valve and the fluid valve, the latter is enabled to operate within the cylindrical portion of the casing without actually touching the walls thereof, so that the friction, which would result from the peripheral contact and a peripheral 100 guide, is eliminated, and the sticking of the valve is effectually prevented. Also the noise, which is sometimes caused by peripheral guiding means, is prevented. The valve seat 12^a, which is arranged at the upper end of a vertical fuel passage 13 and which forms a projecting nozzle, is provided with a reduced threaded portion 14, which engages an interiorly threaded socket or recess 15 at the upper end of the said 105 passage. This enables the valve seat to be readily removed and replaced, but the valve 110

seat may be integral with a vertical tubular portion 16, forming the walls of the passage 13.

In practice the fuel supply may be located at a higher elevation than the valve to produce a gravity feed, thereby automatically priming the carburetor on turning the engine crank and lessening the cranking of the engine. The upper portion of the tubular valve stem of the fluid valve is arranged in an upper tubular guide 17, formed integral with the upper section of the casing and depending from the top wall thereof. The stem 7 of the fuel valve extends through the tubular stem of the fluid valve and projects above the same and is adapted to have its movement limited by an adjusting screw 18, which is mounted at the upper or outer end of the tubular guide but in practice the diameter of the fuel supply passage and the size of the air inlet openings 19 can be made precise, so that no adjusting device will be required. The adjusting screw 18 is mounted at the upper or outer end of the tubular guide 7. It is preferable, however, to employ an adjusting device for enabling the fuel valve to be adjusted to suit the varying conditions of the temperature, atmosphere, etc. The adjusting screw 18 is equipped with a lock nut 20 for securing it in its adjustment. Various other forms of adjusting devices may be employed for limiting the movement of the fuel valve and varying the length of the stroke of the same.

A coiled spring 21 is arranged on the tubular stem 6 and interposed between the lower end of the upper guide 17 and the fluid valve for urging the latter downwardly to hold the same against the collar 12 to seat the fuel valve. The fluid valve is not seated, and operates in opening to separate or depart from the cylindrical portion of the casing. This enables the fluid valve to close the fuel valve and control the opening of the same. The fluid valve is opened by the suction created by the piston in the cylinder of the engine, and the valve casing increases in diameter above the cylindrical portion 4, which receives the fluid valve. This will permit the mixture of air and gasoline or other fuel to readily pass by or around the fluid valve through the valve casing. The suction also operates to open the fuel valve, but it is preferable to interpose a coiled spring 22 between the collar 12 and the valve seat to actuate or assist in actuating the fuel valve in the opening movement thereof. When the fluid valve is opened through suction, it releases the fuel valve, which is limited in its opening movement by the adjusting screw 18, and it will be clear that the limiting of the opening of the fuel valve and the adjustment thereof does not affect the opening movement of the

fluid valve for a given suction and the said fluid valve, after releasing the fuel valve, operates independently thereof so as to maintain a constant suction controlled travel. This prevents any adjustment of the fuel valve from affecting the draft of the engine. The spring 22 owing to its particular arrangement does not resist the opening movement of the fluid valve, but operates to assist the opening movement of the same.

When the fuel valve is open, its tapered lower end is arranged in spaced relation with the fuel passage and it operates to spray the gasoline, or other fuel to cause the same to mix thoroughly with the air, and in order to increase the mixing of the fuel and the air, the air passage of the valve casing is constricted at the fuel valve to bring the air closer to the fuel and to increase the rapidity of the current of air produced by the suction of the engine. This is preferably effected by making the lower section hollow to form an inner wall 23 and an outer wall. The inner wall is approximately V-shaped in vertical section to constrict or contract the air passage around the fuel valve, and the intervening space 24 between the inner and outer walls of the hollow section of the casing is designed to be utilized as a water jacket, 95 suitable inlet and outlet openings 25 and 26 being provided for this purpose.

The air inlet openings 19 are formed in a disk 27 and are arranged in an annular series, and are adapted to coöperate with openings 28 of an adjustable disk or closure 29, mounted on the tubular portion 16 at the lower or outer face of the disk 27 and provided with curved slots 30 and 31 for the reception of screws 32 and 33. The screws, which engage threaded perforations of the disk 27, are adapted to clamp the rotary disk or closure 29 in its adjustment. In this form of invention adjusting means for controlling the passage of air and separate adjusting means for controlling the flow of the fuel are provided, but the air controlling device may be omitted and the adjustment effected through the fuel valve. The valve casing is equipped with a throttle valve 34 of the usual construction, and the terminal portion of the valve casing may be constructed in any manner to adapt it for the particular engine with which it is to be used.

In the foregoing description I have particularly set forth certain details of construction for the purpose of conveying a clear understanding of my invention, but it is my purpose to define in the claims the exact scope of my invention.

Having thus fully described my invention, what I claim as new and desire to secure by Letters Patent, is:—

1. A valve mechanism for carburetors including a fuel valve, means for opening the

same, adjusting means for limiting the travel of the fuel valve, and a suction controlled fluid valve arranged in closing to actuate the fuel valve to positively close the same, 5 said fluid valve having a free opening movement independent of the length of travel of the fuel valve and unresisted by the adjustments of the latter, whereby the stroke of the fuel valve may be shortened to any extent without retarding the fluid valve as influenced by suction.

2. A valve mechanism for carburetors including a valve casing having an air passage and provided therein with a fuel passage, a fuel valve arranged to seat itself on the end of the fuel passage and having a stem, an adjusting device for limiting the movement of the fuel valve, a suction controlled fluid valve having a tubular stem receiving and guiding the stem of the fuel valve, said fluid valve being arranged to actuate the fuel valve in the closing movement thereof and being unresisted in its opening movement by the adjustment of the 25 fuel valve, whereby the stroke of the fuel valve may be shortened to any desired extent without retarding the fluid valve as influenced by suction, guiding means for the fluid valve, and a spring for actuating the 30 fluid valve in the closing movement thereof.

3. A valve mechanism for carburetors including a valve casing having an air passage and provided therein with a fuel passage, a fuel valve arranged to seat itself on the end of the fuel passage and having a vertical stem, a stop located above the stem of the fuel valve for limiting the opening movement of the latter, a suction controlled fluid valve having a vertical tubular stem receiving and guiding the stem of the fuel valve, said tubular stem being extended below the fluid valve and arranged to actuate the fuel valve in the closing movement thereof, and a tubular guide located between the

fluid valve and the end of the fuel passage 45 and receiving and guiding the lower portion of the stem of the fuel valve.

4. A valve mechanism for carburetors including a valve casing having an air passage and provided therein with a fuel passage, a 50 fuel valve arranged to seat itself on the end of the fuel passage and having a stem, a suction controlled fluid valve having a tubular stem receiving and guiding the stem of the fuel valve, said fluid valve being arranged to 55 actuate the fuel valve in the closing movement thereof, a tubular guide extending from the wall of the casing and receiving one end of the tubular stem of the fluid valve, an adjusting device mounted at the 60 outer end of the tubular guide and forming a stop for the stem of the fuel valve to limit the opening movement of the latter, and a separate guide located between the fluid 65 valve and the end of the fuel passage and guiding the lower end of the said tubular stem.

5. A valve mechanism for carburetors including a valve casing having an air passage and provided therein with a fuel passage, a 70 fuel valve arranged to seat itself on the end of the fuel passage and having a stem, a suction controlled fluid valve having a tubular stem receiving and guiding the stem of the fuel valve, said fluid valve being ar- 75 ranged to actuate the fuel valve in the clos- ing movement thereof, a guide located be- tween the fuel passage and the fluid valve and receiving and guiding the said tubular stem, and means for preventing rotary 80 movement of the latter.

In testimony, that I claim the foregoing as my own, I have hereto affixed my signature in the presence of two witnesses.

WILLIAM S. GUTHRIE.
